UNITED STATES PATENT OFFICE.

LÉON EMILE RÉMONDY, OF PARIS, FRANCE.

TIME-FUSE CONTAINER FOR TIME AND PERCUSSION FUSES.

Application filed February 5, 1924. Serial No. 690,813.

To all whom it may concern:

Be it known that I, LÉON EMILE RÉMONDY, a citizen of the Republic of France, resident of Paris, France, have invented new and useful Improvements in Time-Fuse Containers for Time and Percussion Fuses, which is fully set forth in the following specification.

The present invention relates to a retarding device for percussion fuses, and more specifically applicable in combination with fuses of the type described in Patent No. 1,459,075, which operate by combined ramming in and inertia.

Fig. 1 of the accompanying drawing is a sectional elevation of a fuse support in which a fuse of this type and a retarding device in accordance with the invention are mounted; Figs. 2, 3 and 4 are sectional elevations of modifications.

The essential characteristic result obtained by the new retarding device consists in that the retarding composition therein is protected from any direct shock of the gases, flames or explosion débris resulting from the operation of the firing mechanism, these shocks being the more dangerous accordingly as the explosive used for detonating said mechanism is the more powerful.

In accordance with the invention, the retarding composition is placed in the front portion of a sleeve which fits in the rear part of the axial chamber of the fuse support or "fuse body"; this front part of the sleeve

has a diameter smaller than the cavity of the fuse support and is protected by an extra thick and suitably shaped deflecting shield, capable of stopping or retarding the movement of any solid material, while directing

the gases and flames, which can not reach the retarding composition except through the annular space between the fuse support and the sleeve and through flash holes perforated in the longitudinal wall of this latter.

The retarding composition in the reduced portion of the sleeve may be placed in direct contact with a charge of uncom-pressed, quick-burning powder forming a relay for the transmission of fire to the detonator.

In the exemplary embodiment illustrated in Fig. 1, A designates the fuse body screwed in the head of the projectile, and at the free end of which a fuse G, of the type described in the previously mentioned patent, is retained by means of a pin g.

In accordance with the invention, the retarding device comprises a sleeve which fits without play, in the rear end of the cavity *a* of the fuse body A. The closed front part *B*¹ of this sleeve is of smaller diameter, so as to leave an annular space *a*¹ between its outer wall and the inner wall of the cavity *a*. The reduced portion of the sleeve is protected by a mass of metal *B*² of suitable form (conical, ovoid or otherwise) so as to form a deflecting shield, for the purpose herein-before indicated. The retarding or time-burning composition D is placed in the front part *B*¹, having grooved walls, of the sleeve, and access to this composition by the gases or flames arising from the fuse G is impossible until after their passage through the annular space *a*¹ and through the openings *b* perforated in the longitudinal wall of the part *B*¹.

The retarding composition may be placed in direct contact with a charge E of uncom-pressed, quick-burning powder, which forms a relay.

The sleeve, by means of a flange *b*¹ and, if desired, with the interposition of a felt or other packing washer F, bears against the rear end of the fuse support, and is closed at the rear by means of a thin cap C, the edge of which is folded over on the flange *b*¹, and the entire assemblage is retained in position by the detonator I screwed in the fuse support, with the interposition of a felt washer H.

The openings *b* may be of any suitable number and at different levels; a variable number thereof may be perforated before the retarding device is positioned. As shown on the modification of Fig. 2, these openings are suitably arranged in rows and distributed over the surface of the part *B*¹, and may normally be closed by suitable pins *P*¹, *P*² screwed in the fuse support and the countersunk heads of which are accessible from the exterior to remove the same to provide the desired opening for the selected period of retardation.

During operation of the fuse, the gases, flames or splinters arising therefrom and projected rearwardly, can not directly strike the retarding composition D, since they are received by the deflecting shield *B*², which prevents them from destroying the retarding composition through shock and assures proper operation thereof.

The fire can not reach the retarding or

time-burning composition D except through the annular space a^1 surrounding the retarding composition and through the openings b . The form of the deflecting shield B^2 facilitates the passage of the jets of gas or flame, the shock of which has been deadened, toward these openings.

It is furthermore to be noted that, the front surface of the retarding composition D being behind an extra thick part forming a shield, the result of the ignition of said composition will have a tendency to be advanced toward the least resistant wall, formed by the thin cap C.

15 The only element of the retarding device to be machined is a smooth sleeve without a screw thread. The same type of retarding device may be used for a series of different periods of delay, and the duration of the 20 delay may be modified according to the number and position of the openings uncovered.

It is obvious that the construction shown, which is of the simplest, is not the only possible form. The sleeve B— B^1 , with the extra thick shield end B^2 may be made of two parts assembled by any suitable means, for example, by screwing, setting, or swaging.

As a modification, the deflecting shield may be formed as shown on Fig. 3, as a separate thimble forming a cap and fitted on the uniformly thick sleeve. The thimble is then perforated and the adjustment of retardation will be effected by rotation of the thimble to uncover the perforations b of the sleeve to a greater or less extent. The thimble, through a small collar b^3 bears against a shoulder a^2 of the fuse body A.

Fig. 4 shows another embodiment in sectional elevation.

40 In this form of construction the sleeve B— B^1 which contains the retarding composition D in the front part of lesser diameter and the quick-burning powder E forming the relay in its rear part of greater diameter, has its rear portion fitted in the rear element A' of a fuse body formed in two parts A—A'. The front part B^1 of the sleeve with the deflecting shield B^2 , projects 45 within a chamber formed in the rear of the element A of the fuse body, leaving the annular space A'. This element A, forms the fuse support proper and is attached to the rear element A' by screwing or other suitable means. The immovability of the retarding device B— B^1 is assured by the contact of its rear surface b^1 against an inner shoulder A^2 of the element A' of the fuse support and by the rear surface a^2 of the

element A bearing on the shoulder formed between the two parts B¹ and B.

With this method of mounting it is possible to withdraw the retarding device or to position it without it being necessary to withdraw the part of the fuse body in which the detonator is fitted from the projectile and without having to remove the detonator from the fuse body, it being sufficient to unscrew the element A forming the fuse support proper in order to release the retarding device.

The retarding device provided with the deflecting shield, which forms the subject of the invention is, moreover, suited to the widest range of uses. Instead of being used as an easily removable or fixed retarding device, it may be arranged so as to be moved transversely or angularly at the interior of the fuse by any suitable means.

What I claim is:

1. A retarding device for percussion fuses comprising a chambered fuse-body having a percussion fuse, a sleeve within said chamber carrying a mass of relay explosive and a time-burning composition, a massive shield between said percussion fuse and time-burning composition, an annular passage around said time-burning composition and in open communication with the chamber in front of said shield, a graded series of ports between said passage and composition, and removable means closing said ports.

2. A retarding device for percussion fuses comprising a sectioned fuse-body, a chamber in said body having a percussion fuse, a sleeve fitting snugly within said chamber and having a reduced forward portion, a time-burning composition in said reduced portion and a relay explosive in said sleeve, the side walls of said reduced portion having a plurality of perforations in open communication with said chamber, and a massive shield between the percussion fuse and the said reduced portion of the sleeve.

3. A retarding device for percussion fuses comprising a chambered fuse-body having a percussion fuse, a sleeve fitting snugly within said chamber and having a reduced forward portion, a thimble-shaped massive shield fitted on said reduced portion and having apertures through the side walls of said thimble and reduced portion, a relay explosive in said sleeve and a time-burning composition in said reduced portion.

In testimony whereof I have signed this specification.

LÉON EMILE RÉMONDY.
